UNITED STATES PATENT OFFICE.

WILLIAM HENRY WADSWORTH, OF CHICKASHA, OKLAHOMA.

RAILWAY-TIE.

1,269,345.

Specification of Letters Patent. Patented June 11, 1918.

Application filed May 15, 1917. Serial No. 168,785.

To all whom it may concern:

Be it known that I, WILLIAM HENRY WADSWORTH, a citizen of the United States, residing at Chickasha, in the county of 5 Grady and State of Oklahoma, have invented certain useful Improvements in Railway-Ties, of which the following is a specification, reference being had therein to the accompanying drawing.

10 The invention relates to railway ties, and more particularly to the class of concrete ties and braces for railway rails.

The primary object of the invention is the provision of a tie and brace wherein the 15 brace is connected with the fasteners for holding the rail in place upon the tie, while the tie carries a block of fibrous material having the requisite resiliency so as to withstand vibrations and to relieve the vibrations and jars resultant in the use of the 20 rail.

Another object of the invention is the provision of a tie of this character wherein the bearing block for the rail is anchored with- 25 in the body of the tie and constitutes a cushion for said rail, the fasteners for the rail being engaged in the bearing in a novel manner so that the rail can be secured on the bearing or removed therefrom should the 30 occasion require.

A further object of the invention is the provision of a tie of this character which is simple in construction, thoroughly reliable and efficient in its purpose, strong, durable 35 and inexpensive in manufacture.

Other objects will be in part obvious and in part hereinafter set forth.

The invention accordingly consists in the features of construction, combination of ele- 40 ments and arrangement of parts which will be exemplified in the construction herein- after described, and the scope of the applica- tion of which will be indicated in the ap- pended claim.

45 In the drawing:

Figure 1 is a fragmentary top plan view of a track, showing the rails applied to the ties constructed in accordance with the invention;

50 Fig. 2 is an elevation, partly in section, showing the connecting rod between the ties.

Similar reference characters indicate corresponding parts throughout the several views of the drawing.

55 Referring to the drawing in detail, A designates generally the body of the tie; it

being understood, of course, that one of these ties is employed for each rail and is made from cementitious material having the required width, thickness and length. Embedded in the body A is a cushioning block 5 preferably made from wood, although the same can be made from any other material having the desired cushioning effect, the block being of substantially dove tail shape in cross section, and is countersunk within the body A so that the top face of said block protrudes a slight distance above the plane of the top face of said body A of the tie, and upon this block 5 rests the base of the rail 6, which is of the ordinary well known construction.

Passed through the block 5, vertically thereof, are headed bolt members 7 which are located at opposite sides of the base of 75 the rail 6, and the heads 8 of which engage with the bottom face of the block 5, while engaged on these bolt members 7 are rail clamps 9 which overlap the base of the rail 6 and are held in such position through the 80 medium of nuts 10 threaded on the bolt members 7 and working against the top faces of the clamps 9 so that in this manner the rail 6 is securely fastened upon the block 5, which absorbs shocks and jars imparted to 85 the rail 6 by the rolling stock traffic thereon.

Arranged between the rails 6 of the track and connected with the innermost vertical bolt members 7 at the inner side of said rails is a rod 11, and this rod is held in place by 90 the nuts 10 engaged on the innermost bolt members so that the ties A cannot spread laterally when the rails 6 are subjected to heavy loads.

It is, of course, understood that the block 95 5 is embedded within the body A of the tie prior to the hardening thereof in the molding of the cementitious material from which the same is made. If desired, the block 6 can be treated with preserving substance to 100 avoid the decaying thereof or otherwise deterioration due to climatic changes.

From the foregoing description, taken in connection with the accompanying drawing, the construction and use of the herein de- 105 scribed railroad tie will be readily apparent and, therefore, a more extended explanation has been omitted.

Having thus described my invention, I claim:

110 In a railway tie, a cementitious body, a cushioning block embedded in said body

when the body is being molded and having its upper surface disposed above the plane of the upper surface of the body to form a bearing for a rail, vertical bolt members engaged through the block, heads on the bolt members bearing against the bottom of the block and anchored in the body when the body is being molded to prevent accidental displacement of the block, the upper ends of 10. the bolt members projecting above the block, rail clamps mounted on the bolt members

and adapted to engage a rail, nuts threaded on the upper projecting ends of the bolt members and acting against the rail clamp and a tie rod disposed about the innermost 15 bolt member for preventing lateral spreading of said body and being retained in position by the nut on the innermost bolt member.

In testimony whereof I affix my signature. 20

WILLIAM HENRY WADSWORTH.
